UNITED STATES PATENT OFFICE.

JAMES T. CALLANAN, OF PARKERSBURG, WEST VIRGINIA, ASSIGNOR TO
THE PARKERSBURG MACHINE COMPANY, OF PARKERSBURG, WEST
VIRGINIA, A CORPORATION OF WEST VIRGINIA.

OIL-SAVER.

No. 818,740.

Specification of Letters Patent.

Patented April 24, 1906.

Application filed August 31, 1905. Serial No. 276,551.

To all whom it may concern:

Be it known that I, JAMES T. CALLANAN, a citizen of the United States, residing at Parkersburg, in the county of Wood and State 5 of West Virginia, have invented certain new and useful Improvements in Oil Savers, of which the following is a specification, reference being had therein to the accompanying drawings.

10 In those oil-savers in which a tube or barrel reciprocates through the casing-head difficulty has been experienced in preventing oil or gas, or both, from escaping through the barrel, no efficient means having been provided hereto for so packing the cable within the barrel as to prevent leakage. As is well known in the art, when an oil-saver is in place during the operation of drilling the tube or barrel reciprocates with the drilling-cable, 15 being clamped thereto. When operating a swab attached to the cable, the barrel is anchored or secured to the casing-head, the cable reciprocating through the barrel at such times.

20 The primary object of the present invention is to so pack the cable within the barrel that leakage is prevented as well when the cable is reciprocating through the barrel as when the barrel is secured to and reciprocates 25 with the cable.

A further object is to provide improved means for clamping the barrel to the cable.

Still further object is to improve the construction of the stuffing-box, through which 30 the cable reciprocates.

For the accompanying drawings, Figure 1 is a vertical sectional view of an oil-saver constructed in accordance with my invention. FIG. 2 is a plan view, taken on line 2

40 of FIG. 1. Referring to the drawings, 2 designates the upper end of the casing of an oil or gas well, and 3 is the casing-head, having the lead or discharge-pipe connections 4. Fitting within 45 in and closing the top of the casing is the usual cap 5, held in place by screws 6.

7 is the barrel, which reciprocates through the casing-head and cap 5, and to provide a tight joint the cap is extended to form a stuffing-box 8, into which gland 9 is forced on packing 10 by the screw-cap 11. Thus leakage is prevented around the barrel.

Secured to the upper end of the barrel is head 12, which is open for the passage of the cable 13. The upper end of the head is extended to form stuffing-box 14, and having 55 threaded union therewith is head 15, which operates to depress gland 16, and thereby compress packing 17 closely around the cable. By this means the cable is tightly packed, so that whether the cable is working 60 with or independently of the barrel no oil or gas can escape from the barrel by passing upward around the cable.

In the upper portion of head 15 the cable- 65 passage is intersected by the horizontal recess 18, and confined therein by screw 19 is the cable-clamping slide 20, having a central aperture through which the cable passes. A screw 21 operates to move slide 20 laterally, 70 as shown, thereby securely clamping the cable and causing the working portions of the saver to move therewith. Slide 20 is preferably square, so that as the aperture there- 75 through becomes worn the slide may be turned with either of its four edges toward screw 21.

When operating a swab, the saver-barrel is fixed to the casing-head, head 12 carrying the usual projections 12', which afford convenient means for chaining or anchoring the barrel to the casing-head, with the former in lowered position. At such time clamping-screw 21 is relaxed and the cable is free to reciprocate through barrel 7 and the heads at 80 the upper ends thereof. The cable then reciprocates through stuffing-box 14, but is so packed that the oil or gas cannot escape upwardly therearound.

It is usual to provide the lower end of the 90 reciprocating barrel with a threaded sleeve or collar to form a stop for preventing the barrel from being entirely withdrawn from the casing-head cap, as might sometimes occur through accident. As the threaded sleeve or 95 collar is liable to work loose and drop off, I have provided an integral stop by flaring the lower extremity of the barrel, as indicated at 7'.

I claim—

1. In an oil-saver, the combination of a casing-head, a vertically-reciprocating barrel forming a cable-passage, a stuffing-box secured to the upper end of the barrel, a gland-

compressing head uniting with the stuffing-box and also provided with a cable-passage, and cable-securing means carried by the head.

2. In an oil-saver, the combination of a 5 casing-head, a casing-head cap having a barrel-passage, a barrel, a stuffing-box formed on the upper side of the cap, a gland-compressing cap having threaded union with the casing-head cap, a cable stuffing-box carried 10 by the upper end of the barrel, and cable-clamping means.

3. In an oil-saver, the combination with a 15 barrel adapted to reciprocate vertically and form a cable-passage, a head secured to the upper end of the barrel, the head being extended to form a stuffing-box, a gland-compressing head uniting with the first-mentioned head, and cable-clamping means carried by the gland-compressing head.

20 4. In an oil-saver, the combination with a barrel adapted to reciprocate vertically and form a cable-passage, of a head carried by the barrel formed with a cable-passage and also with a transverse angular recess intersecting 25 the cable-passage, a clamping-screw entering the passage, and an angular slide movable within the passage and of such form that any

edge thereof may be presented to the clamping-screw, the slide having a cable-aperture.

5. A cable-securing device for oil-savers 30 comprising a head having a vertical cable-passage and a transverse recess intersecting said passage, a cable-clamping slide operative within the recess, the slide being of such size and shape that it may be variously inserted 35 within the head-recess with different portions thereof in engagement with the cable, and slide-actuating means.

6. A cable-securing device for oil-savers 40 comprising a head having a vertical cable-passage and a transverse recess of rectangular form intersecting said passage and at one end open through a side face of the head, a substantially square cable-clamping slide adapted to be variously inserted within said recess 45 thereby engaging different portions thereof with the cable, and slide-securing means.

In testimony whereof I affix my signature in presence of two witnesses.

JAMES T. CALLANAN.
